(57) **CLAIM**

The ornamental design for an air flow directing fixture for heating, air conditioning and ventilation devices, as shown and described.

DESCRIPTION

FIG. 1 is an isometric front view of the air flow directing fixture, showing my new design;

FIG. 2 is an isometric rear view thereof;

FIG. 3 is a front plan view thereof;

FIG. 4 is a right side view thereof, the left side view being the mirror image thereof;

FIG. 5 is a bottom side view thereof, the top side view being the mirror image thereof; and,

FIG. 6 is a rear view thereof.
